UNITED STATES PATENT OFFICE.

WILLIAM K. BENEDICT, OF NEW YORK, N. Y., ASSIGNOR TO THE CO-OPERATIVE BUILDING PLAN ASSOCIATION, OF SAME PLACE.

DESIGN FOR THE EXTERIOR OF A RESIDENCE.

SPECIFICATION forming part of Design No. 19,547, dated December 31, 1889.

Application filed December 7, 1889. Serial No. 332,973. Term of patent 3½ years.

To all whom it may concern:

Be it known that I, WILLIAM K. BENEDICT, of New York, in the county of New York and State of New York, have invented and produced a new and original Design for the Exterior of a Residence, of which the following is a specification, reference being had to the accompanying drawings, forming a part thereof.

10 Figure 1 represents a perspective view of a residence showing my design. Fig. 2 represents a horizontal section or plan of the first story. Fig. 3 represents a horizontal section or plan of the second story.

15 Similar letters of reference designate corresponding parts in all the figures.

A residence embodying my design is generally rectangular in the ground plan, and comprises a main portion and an L, together 20 with a first and second story and an attic story, the whole being surmounted by gable roof F G.

At the front of the first story is a porch A,

to which a flight of steps a leads, surmounted by an arch-shaped roof a'. To one side of the 25 roof a' is a shed-roof a². At the corner of the residence, beyond the shed-roof a², is a tower B. Above the roofs a' a² the front of the residence is substantially flat.

An L C extends from one side of the residence, the side of the L being substantially flat.

The tower B is substantially circular, and is surmounted by an ogee-shaped dome D. Pillars d extend between the dome D and the 35 top of the tower B.

Upon one side of the residence is an octagonally-shaped bay E.

What I claim is—

The design for the exterior of a residence, 40 substantially as herein shown and described.

WILLIAM K. BENEDICT.
